UNITED STATES PATENT OFFICE.

JOHN W. LAMBERT, OF ANDERSON, INDIANA.

APPARATUS FOR COOLING GAS-ENGINE CYLINDERS.

SPECIFICATION forming part of Letters Patent No. 624,827, dated May 9, 1899.

Application filed October 16, 1897. Serial No. 655,454. (No model.)

To all whom it may concern:

Be it known that I, JOHN W. LAMBERT, a citizen of the United States, residing at Anderson, in the county of Madison and State 5 of Indiana, have invented certain new and useful Improvements in Apparatus for Cooling Engine-Cylinders, of which the following is a specification, reference being had therein to the accompanying drawings, in which—

15 Figure 1 is a side elevation of the apparatus, parts being broken away to more fully show its construction; and Fig. 2 is a vertical sectional view of a portion of the apparatus.

This invention relates to an apparatus for 15 cooling gas-engine cylinders by causing a circulation of water around the same, said water after it leaves the water-jacket surrounding the cylinder being cooled by a suitable medium and then returned to the water-jacket.

The object of the invention is to provide an apparatus which will cause a constant circulation of the water and secure an effective cooling of the heated water without causing 25 a too rapid evaporation thereof.

Referring to the various parts by numerals, 1 designates a gas-engine cylinder which is provided with a water-jacket of any desired construction. Leading from the top of the 30 water-jacket upward to a tank 2 is a pipe 3, through which the water which has passed through the jacket and become heated passes up to the tank. This tank is supported at a suitable height above the cylinder, and the 35 pipe 3 enters through the bottom thereof, its end extending vertically to a point a suitable distance below the normal water-level in the tank. Surrounding a portion of this pipe within the tank and extending above its upper end is the upper vertical exit end of an air-blast pipe 4, whose inlet end is extended outside of the tank, said pipe at a point between its inlet and its outlet end being carried above the water-level in the tank, as at 40 10, to form a trap to prevent the water flowing out through said blast-pipe when the blast is reduced. Surrounding the exit end of the blast-pipe is a cylindrical hood 5, which is somewhat larger in diameter than the blast-pipe, so that a space is formed between the pipe and the hood. The lower end of this

hood is open and extends below the end of the blast-pipe, and its upper end is closed with a hollow inverted conical top 6. The apex of the conical deflector is over the center of the open end of the blast-pipe and its base is equal in diameter to the hood, so that an annular V-shaped recess is formed at the top of the hood. Below the lower open end of this hood is mounted a circular deflector 7, 55 whose upper surface inclines downward and outward and whose inner edge fits tightly around the blast-pipe. The outer edge of the deflector extends out beyond the outer circumference of the hood 6, so that the 60 mingled water and air will contact therewith as they pass down out of the hood. The parts may be supported as desired, a simple manner being shown in the drawings, wherein the deflector is supported on the blast-pipe, and the hood is carried by the deflector by means of short legs 8. Connected to the inlet end of the blast-pipe is a blower 9, which is connected by a suitable belt or driving means to the driving-pulley of the gas-engine or other 65 source of power. Water from the bottom of the tank flows through a pipe 11 to the lower portion of the water-jacket around the engine-cylinder. 70

In operation the tank is filled with water 80 to a point somewhat above the end of the inlet-pipe 3. Whenever the engine is in operation, the fan 9 is running and is forcing a blast of air through pipe 4. This blast of air at the beginning of the operation throws the 85 water which may have accumulated in said pipe beyond the trap 10 up into the hood 5 and over the cone 6 and into the V-shaped recess, formed by the cone and the vertical wall of the hood. From that point the 90 mingled water and air pass down to the deflector 7 and then out into the tank, the air passing out at the top thereof. When the water in the blast-pipe has been blown out into the tank, the level of the water in the 95 tank will have been thereby made higher than that in pipe 3, and because of this difference in the level of the water in the tank and in the pipe the water will be gently forced out of the pipe 3. When this water flowing out 100 of pipe 3 meets the upward-rushing air in the blast-pipe, it is carried forcibly up into the

hood and sprayed over the cone and walls of the hood, being cooled thereby. By thus constantly lifting the water out of the blast-pipe into the tank the water in the tank is maintained higher than that in pipe 3, and a constant flow of water is thereby kept up through the jacket around the cylinder and up through pipe 3. As the blast of cool air rushes in through pipe 4 it first surrounds the upper part of water-inlet pipe 3 and tends to cool it. It then rushes up around said pipe and carries the inflowing water into the hood, where the water is cooled by commingling with the cool air and coming in contact with the walls of the hood. A greater portion of the steam or vapor from the hot water will be condensed by the cool air, the walls of the cone and hood, and the deflector; so that the water lost by evaporation will be reduced to a very small percentage. It will be observed, therefore, that the hood or an equivalent device is an essential feature in that it receives the impact of the spray and separates the water from the air and returns it to the tank while permitting the air to escape laden with but a minimum of vapor. It will thus be seen that a constant positive circulation of water is maintained through the water-jacket and that the blast of air which causes this circulation cools the water by commingling the water and spraying it. In this way the use of a common pump for maintaining a positive and ample circulation is avoided and the water is quickly and materially reduced in temperature, rendering it necessary to keep but a small supply of water in the tank, which is a great desideratum in many cases.

It is obvious that it is not absolutely essential that the water-level be above the open end of pipe 3, since the blast of air will tend to create a partial vacuum at the end of said pipe, which will cause the atmospheric pressure to force the heated water up through said pipe, the water as it issues from the end of the pipe being taken up bodily by the blast and thrown forcibly into the hood.

Having thus fully described my invention, what I claim, and desire to secure by Letters Patent, is—

50 1. In a cylinder-cooling apparatus, the combination of a cylinder and water-jacket therefor, a water-tank, a cool-water pipe leading from the tank to the jacket, a hot-water pipe leading from the jacket to the tank and terminating within the same, a blast-pipe so disposed at the end of the latter pipe in the tank as to spray and commingle the air with the hot water as it escapes at the end of the pipe, and a device beyond the ends of the blast-pipe and hot-water pipe to receive the impact of the spray and return the water to the tank while permitting the air to escape, substantially as and for the purposes set forth.

2. In an apparatus for cooling engine-cylinders, the combination of a water-jacket sur-

rounding the cylinder, a tank above said jacket, a water-pipe leading from said tank to the jacket, a water-pipe leading from the jacket to the tank, this latter pipe leading into the tank and being open at its end, a blast-pipe directing a blast of air around said pipe at its end, a hood beyond the end of the blast-pipe, and a blower connected to the blast-pipe, whereby a constant circulation may be maintained through the jacket, substantially as described. 70

3. The combination of a water-jacket, a tank above said jacket, a water-pipe leading from said tank to the jacket, a water-pipe leading from the jacket to the tank, the upper end of this pipe being open and terminating in the tank, a blast-pipe directing a blast of air at the upper end of this pipe, the end of said blast-pipe extending beyond the end of the water-pipe, and means for causing 80 a blast through the blast-pipe, whereby the air-blast will not only commingle with and cool the water but will also maintain a forced circulation thereof, and a device beyond the blast-pipe to receive the impact of the spray 85 and to separate the spray from the air, substantially as described.

4. The combination of a water-jacket, a tank above said jacket, a water-pipe leading from the tank to the jacket, a water-pipe 95 leading from the jacket to the tank, the upper end of this pipe being open, a hood over the end of said blast-pipe, said hood being closed at its upper end and open at its lower end, means for causing a blast of air to commingle with and spray the water into said hood, substantially as described. 100

5. The combination of a water-jacket, a tank above said jacket, a water-pipe leading from the tank to the jacket, a water-pipe 105 leading from the jacket to the tank, the upper end of this pipe being open, a blast-pipe directing an upward blast of air around the upper end of the water-pipe, means for causing a blast through the blast-pipe, and a conical deflector over the water-pipe and blast-pipe, substantially as described. 110

6. The combination of a water-jacket, a tank above said jacket, a water-pipe leading from the tank to the jacket, a water-pipe 115 leading from the jacket to the tank, the upper end of this pipe being open, a blast-pipe directing an upward blast of air around the upper end of the water-pipe, means for causing a blast through the blast-pipe, a hood 120 over the end of said blast-pipe, said hood being closed at its upper end and open at its lower end, and a deflector extending outward from the outer surface of the blast-pipe and below the lower edge of the hood, substantially as described.

7. In an apparatus for cooling engine-cylinders, the combination of a water-jacket surrounding the cylinder, a tank above said jacket, a water-pipe leading from the tank to 130

the jacket, a water-pipe leading from the jacket to the tank, an upwardly-extending blast-pipe surrounding the upper end of this pipe, said blast-pipe terminating above the water-level in the tank, and a device above the upper end of said blast-pipe adapted to direct the upward blast laterally away from the end of said pipe, whereby the air-blast will not only commingle with and cool the

water but will also maintain a forced circulation thereof, substantially as described.

In testimony whereof I affix my signature in presence of two witnesses.

JOHN W. LAMBERT.
